SKIP BOOM AND SKIP FOR CONCRETE
PAVERS

Fred L. Dake, Nunda, N. Y., assignor to The
Foote Company, Inc., Nunda, N. Y., a corpora-
tion of Delaware

Application October 10, 1931. Serial No. 568,148

15 Claims. (Cl. 214—130)

My invention relates to new and useful im-
provements in concrete pavers, and more espe-
cially to the skip and the skip boom and the man-
ner in which they are operated.

5 Still another object of the invention is to pro-
vide a differential self-raising skip boom, which
boom is normally flush with the upper or super-
structure of the paver to thereby cut down the
normal height of the machine.

10 As is well known, most pavers in use today have
a frame extending from the top of the paver up-
wardly to provide a means over which a cable
may pass to elevate the skip, and inasmuch as
pavers are relatively high anyway, the extra
15 frame often proves an inconvenience for ship-
ment, as it is apt to contact with the top of cul-
verts or bridges, making it generally necessary,
therefore, to lower this top frame when the
machine is being transported or moved from one
20 place to another.

An object of the present invention, therefore, is
to produce a paver of the well-known Foote type,
which dispenses with the well-known A-frame,
which A-frame is shown in Patent No. 1,565,634,
25 granted December 15, 1925, to Charles E. Foote
for Boom drives.

Still another object of the invention is to pro-
vide a paver with a skip boom that normally lies
parallel with the top of the paver and which has
30 a differential movement, so that as the skip is ele-
vated, the skip boom also elevates but at a lower
rate of speed than the skip.

Still another object of the invention is to pro-
vide a differential self-raising skip boom, wherein
35 the lifting cable of the skip may be what I term a
center line lifting one, rather than having a cab-
ble, or cables, that extends to the opposite sides
of the skip.

Still another object of the invention is to pro-
40 vide a differential skip boom, wherein the first
movement of the skip raises the skip boom gradu-
ally but the rate of speed of the boom increases
as the skip approaches its full raised position.

Still another object of the invention is to pro-
45 vide a skip boom and cable and to so thread the
cable that the lifting load will be reduced and,
at the same time, allow the skip to raise in ap-
proximately the time that it has with other forms
50 of raising means or slightly faster.

Still another object of the invention is to pro-
vide a skip and skip boom and lifting cable, all
of which parts are so associated that the usual
top frame is dispensed with, while, at the same
55 time, means are provided for so supporting the

cable that the skip may be elevated just as quick-
ly and rapidly and safely as before.

With these and other objects in view, the in-
vention consists in certain new and novel ar-
rangements and combination of parts, as will be
hereinafter more fully described and pointed out
in the claims.

Referring now to the drawings showing a pre-
ferred embodiment of the invention.

Fig. 1 is a fragmentary side elevation of a 65
paver showing the skip in its lowered position and
showing the skip boom in its normal position;

Fig. 2 is an end view showing the skip in its
lowered position, the dotted lines showing the
skip and skip boom in their elevated position; 70

Fig. 3 is a view similar to Fig. 1, but showing
the skip and skip boom in their elevated position,
the dotted lines showing the said parts in their
lowered or normal position;

Fig. 4 is a fragmentary top plan view of the 75
differential self-raising skip boom and a part of
the skip;

Fig. 4^a is substantially a cross-sectional view
taken on the line 4—4 of Fig. 1;

Fig. 5 is a diagrammatic view showing the paver 80
with the skip and skip boom in their lowered po-
sition and showing a conventional form of boom
and bucket; and

Figs. 6, 7, 8, 9 and 10 are fragmentary dia-
grammatic views showing a form of step by step 85
movement of the skip and also the relative move-
ment of the skip boom therewith.

Referring now more particularly to the several
views, and to Fig. 1 for the moment, there is
90 shown the paver chassis or frame 1, on which
is mounted the drum 2. There is also shown
the uprights 3 of the frame of the paver, while at
the top may be seen a top side frame 4.

It will be understood that I have only shown 95
as much of the paver as is necessary to illustrate
the skip and its elevating means. To the up-
rights 3, there is pivoted the skip 5, the support-
ing rod 6 fitting within bearings 6^a, as clearly
shown in Fig. 1. The skip may be of any pre-
ferred form, and extending across the same may
be the rod 7, on which is mounted the sheave 8.

Taking up next the boom and the manner in
which it cooperates with the skip, reference is
now made to Fig. 4 for the moment. There will
105 be seen the skip boom 9 which comprises two
heavy members 10, which are pivotally mounted,
as at 11, on the cross rod 12. These members 10
are bent inwardly, as at 13, so that they form
practically one solid member at their outer end 110

14. Mounted in this outer end 14 of the composite boom 9 are the two sheaves 15 and 16.

Now mounted respectively on the shaft 17, which shaft extends across the members 10 that form the skip boom, are the two depending arms 18, which are offset, as at 18', and pivoted at their lower ends, as at 19, to the cross bar 19^a, which bar extends through the oppositely positioned plates 20 which are formed on the opposite side of the skip 5.

As also may be seen in Fig. 4^a, there is a brace 21 that extends under the inner end of the skip and between the ends of the rod 6 to thus rigidly support the skip at its inner end, while a similar brace 21' extends to the ends of the shaft 19^a.

The forward end of the skip, as may be seen in Figs. 2, 4 and 4^a, is reduced and turned over slightly, as at 22, to provide against any of the aggregates from spilling from the skip rather than running into the drum of the mixer. In fact, the entire inner end of the skip might be covered, if so desired.

Now referring to the manner of raising the skip, there will be seen in Fig. 1 the skip elevating drum 23, over which the cable 24 is passed, and it will be understood that to operate this cable the drum 23, in turn, will be started and stopped in the usual manner. The cable 24 extends upwardly, as seen, and passes over a sheave 25 mounted in the top side frame of the paver and then extends outwardly over the sheave 15, where it then passes downwardly, as at 26, to pass over the sheave 8 mounted on the skip, and then upwardly, as at 27, over the sheave 16 and then downwardly, as at 28, where it is connected at its outer end, as at 29, to the said bar or rod 7. In other words, there is what might be termed a three-line cable extending between the skip and the skip boom. It will also be noticed from Fig. 4 that this cable 40 is what I term a center line cable, that is, it extends centrally down the boom and centrally of the skip.

Thus, it will be seen as far as the specification has proceeded, that there is no additional top frame extending from the top horizontal frame of the paver to support the skip, as in the former types of Foote pavers. In other words, the paver is substantially flat or level across its top, so that when the paver is moved either on a flat car or trailer or in fact in any way moved from place to place, there is no top frame to be taken down, so that the paver will not strike the top of culverts, bridges, etc.

55

Operation

Supposing the skip is in its lowered position, the several parts of the differential self-raising skip boom and the skip will be in the position, as shown in Fig. 1, and also as shown in the diagrammatic view of Fig. 6. After the skip is loaded with the aggregates, means (not shown) for starting the drum will be operated to thus wind up the cable 24. As the cable is thus wound, the first movement will be a raising of the skip and a slight raising of the skip boom 9. Due to a three-line cable extending to the skip and the arrangement of the sheaves, as shown, the power required to raise the skip will, of course, be less than if only one bight of the cable extended to the skip.

Now, as the skip continues in its upward movement by the winding of the cable on the drum 23, the skip will assume the position as shown 75 in Fig. 7, and, through the floating pivotal point

19 and the floating pivotal points 17 of the arms 18, will push the boom 9 upwardly, it being remembered that the inner end of the skip is pivotally fixed, as at 6. The rate of the upward movement of the skip is substantially twice that of the rate of movement of the boom, so that as the skip is continued in its raising movement it will pass through the relative positions shown in Figs. 8, 9 and 10, and when the skip has approached substantially its upward limit of movement the skip will have practically caught up to the position of the skip boom. Thus, the boom not only provides a support for the cable to elevate the skip but, as the skip raises, moves itself out of the way of the skip or, in other words, moves ahead of it, so that the upward movement of the skip is in no way limited or obstructed by the skip boom which, of course, would be the case if the boom remained in its normal or horizontal position.

The upper limit of travel of the skip is illustrated in Fig. 3, and it will be understood that the skip in raising, pushes the boom ahead of it, but due to the floating pivotal points of the arms 18 and the fixed pivotal point of the skip, the skip nearly overtakes the boom at its uppermost limit of travel. Thus, it will be seen that there is a differential movement existing between the skip and the skip boom and that the boom is a self-raising one, as the upward pivotal movement of the skip, through the arms 18, pushes the skip boom ahead of it and thus out of the way of the oncoming skip.

It will also be seen that the skip boom provides a means for supporting the cable and skip, which boom is raised and lowered as the skip is raised and lowered, thus doing away with the ordinary rigid super-frame.

It is also to be appreciated that a loaded skip is relatively heavy and that substantial means have to be provided for supporting the cable that elevates the skips, while considerable power is also necessary to raise the skip.

With the arrangement just outlined, however, the ordinary form of cable drum may be utilized, as the power necessary is cut down by using the double arrangement of the sheaves and the threading of the cable, as shown, and I have also found that the speed of the skip is practically the same as before or slightly faster.

It is also to be noticed that by providing what might be termed a block and tackle arrangement of the cable between the skip boom and the skip, the cable is always kept taut or, in other words, free from slack, even though there is a differential movement between the skip boom and the skip.

It will be understood, of course, that although I have mentioned that Figs. 5 to 10 show a step by step movement of the skip and boom, the movement will be continuous, and the figures are supposed to outline the different positions during the continuous movement of the skip that the skip will pass through, together with the relative positions of the skip boom.

When the skip is lowered, it will travel faster in its downward movement than the skip boom, but as the skip reaches its lowermost end of travel again, the skip boom will have again assumed the position shown in Fig. 1, that is, flush with the top side frame of the paver.

From the foregoing, it will be seen that I have provided a paver, wherein the ordinary top frame is dispensed with and in its place there is substituted a differential self-raising skip boom.

Furthermore, the power necessary to raise the skip and boom is no more than found necessary with the old form of skip and, at the same time, the rate of travel of the skip is the same as before or even slightly faster.

5 I am aware that it is old to simply dispense with super-frames for the elevating of the skip, and I do not claim my invention as such, but what I do claim and desire to secure by Letters Patent is:

10 1. In combination with a concrete paver, a pivotally mounted skip, a skip boom pivoted at its rear end to said paver and extending directly over the central longitudinal axis of the skip arms pivotally connected to both the skip and the skip boom, a cable for elevating and lowering said skip and an elevating of the skip causing an elevating of said skip boom.

20 2. In combination with a concrete paver, a pivotally mounted skip, a skip boom pivoted at its rear end to said paver and extending outwardly and directly over the central longitudinal axis of the skip an arm pivotally connected to the skip boom at a point remote from the pivotal point of said boom and pivoted also to the skip at a point below the pivotal point of the skip, whereby an elevating of the skip will cause a raising of the skip boom but at a slower rate than the rate of upward movement of the skip.

30 3. In combination with a concrete paver, a pivotally mounted skip, skip boom pivoted at its rear end to said paver and extending out over the central longitudinal axis of the skip, arms pivotally connected to the skip boom at a point remote from the pivotal point of said boom and also pivoted to the skip at a point removed from the pivotal point of the skip, a cable for operating the skip, and a movement of the skip causing a movement of the skip boom but at a different rate thereto.

40 4. In combination with a concrete paver, a skip pivotally mounted at its forward end to the paver, a skip boom pivoted at its rear end to said paver and extending outwardly and directly over the central longitudinal axis of the skip arms pivotally connected to the skip boom at a point removed from the pivotal point of said boom and also pivoted to the skip at a point removed from the forward end of the skip, a cable passing along said boom and connected to said skip whereby a movement of the skip will cause a movement of the skip boom but at a different rate thereto, the cable so threaded between the boom and the skip that the slack caused by the differential movement between the skip and the boom will be taken up.

50 5. In combination with a concrete paver, a pivotally mounted skip and a pivoted skip boom, said boom extending outwardly and directly above the central longitudinal axis of the skip pivotal arms between the boom and the skip, and the pivotal point so arranged that the skip and boom move at a differential rate of speed.

60 6. In combination with a concrete paver, a differential self-raising skip boom, a skip pivotally mounted to the paver and to the skip boom and the boom extending along the central longitudinal axis of the skip, and a cable so threaded between the skip boom and the skip that the differential rate of movement will not cause a slack in said cable.

70 7. In combination with a paver, a pivotal skip, a pivotal skip boom, a center line cable extending along the boom and connected to the skip, and arms pivotally connected at their one end to the skip at a point remote from its pivotal point and at their opposite end pivoted to the skip boom and

likewise at a point remote from the pivotal point of said skip boom to thereby cause a differential movement of the skip boom on the elevating and lowering of the skip by said cable, and the said skip boom being directly over the central longitudinal axis of the skip.

80 8. In combination with a paver, a pivotal skip, a pivotal skip boom extending in a plane directly over the central longitudinal axis of the skip, said skip boom substantially horizontal with the top of the paver, a cable extending along the boom and connected to the skip, pivotal arms so connected to the skip and skip boom as to cause a differential movement between the skip and the skip boom on the elevating and lowering of the skip by said cable, and the said cable so threaded between the skip and skip boom as to reduce the power required to raise the skip.

85 9. In combination with a paver, a pivotal skip, a pivotal skip boom extending along the central longitudinal axis of the skip, said skip boom substantially horizontal with the top of the paver, a center line cable extending along the boom and connected to the skip, pivotal arms so connected to the skip and the skip boom as to cause the 90 boom to raise as the skip is raised but at a different rate of speed thereto, and the cable having three bights extending between the skip boom and the skip to thereby decrease the power necessary to elevate the skip.

95 10. In combination with a concrete paver, a pivotal skip, a differential self-raising skip boom extending along the central longitudinal axis of the skip and cooperating with said skip, a cable extending along said boom and connected to said skip and so connected as to prevent any slack between the skip boom and the skip and to decrease the power load necessary to elevate said skip.

100 11. In combination with a concrete paver, a composite boom having two sheaves at its outer end, a skip pivoted beneath said boom and the central longitudinal axis of the skip being directly beneath the said boom, arms pivoted to the boom and to the paver to cause the boom to elevate when said skip is elevated, and a cable passing along said sheaves and connected to the skip for elevating said skip.

115 12. In combination with a concrete paver, a pivotal skip boom normally horizontal with the paver, a skip pivoted to the paver and the central longitudinal axis of the skip being directly beneath the skip boom, pivotal arms connected between the skip and the pivoted boom and the pivotal points respectively remote from the pivotal points of the skip boom and the skip paver to thereby cause a movement of the skip boom when said skip is moved and at a different rate of speed thereto, a cable extending along the boom and having a multiplicity of bights extending between the skip boom and the skip to thereby reduce the power necessary to raise the skip by the number of bights extending between the skip boom and the skip.

125 13. In combination with a concrete paver, a pivotal skip, means for elevating the same, a pivotal skip boom extending over the central longitudinal axis of the skip, pivotal arms extending between the pivotal skip and the skip boom, and the pivotal points of said arms remote from the pivotal points of the skip boom and the skip paver, respectively, so that the skip will substantially overtake the skip boom during the upward movement of said skip when said elevating means is utilized.

14. In combination with a paver, a pivotal skip and a pivotal skip boom extending directly over the central longitudinal axis of the skip, means pivoted at its one end to the skip boom at a point remote from the pivotal axis of the skip boom, and said means pivoted at its opposite end to the skip at a point remote from the pivotal point of said skip, to thereby cause the said boom to raise when the skip is raised but at a decreased rate of speed thereto.
15. In combination with a paver, a pivotal skip and a normally horizontal pivotal skip boom ex-

tending over the central longitudinal axis of the skip, a cable for elevating and lowering the skip, pivotal arms extending between the skip boom and the pivotal skip and the arms positioned at a point remote from the pivotal point of the skip and the pivotal point of the skip boom whereby the skip boom is raised on an upward movement of the skip but substantially overtaken by the skip as the skip approaches its topmost limit of travel.
